(57) **CLAIM**

The ornamental design for a coaxial connector, as shown and described.

DESCRIPTION

Design patent application Ser. No. 29/216,920 filed concurrently herewith, entitled “Coaxial Connector;” naming William Frederick McDade, et al. as the inventors, commonly assigned to Corning Gilbert Inc.; Design patent application Ser. No. 29/216,935 filed concurrently herewith, entitled “Coaxial Connector;” naming Kathryn M.R. Murphy, et al. as the inventors, commonly assigned to Corning Gilbert Inc.; and Design patent application Ser. No. 29/216,908 filed concurrently herewith, entitled “Coaxial Connector;” naming Donald Andrew Burris, et al. as the inventors, commonly assigned to Corning Gilbert Inc.

FIG. 1 is a top, side, and front perspective view of a coaxial connector showing our new design;

FIG. 2 is a bottom, side, and rear perspective view thereof;

FIG. 3 is a top plan view thereof;

FIG. 4 is a right side elevational view thereof;

FIG. 5 is a bottom plan view thereof;

FIG. 6 is a front end view thereof; and,

FIG. 7 is a rear end view thereof.

The purpose of broken lines in the drawing, including broken lines internal to the coaxial connector and broken lines on the outer surface of the connector depicting ridges, merely illustrate environmental structure or boundaries that form no part of the design to be patented via the present application.
